UNITED STATES PATENT OFFICE

2,065,304

RESPIRATOR

Harvey S. Cover, South Bend, Ind.

Application January 9, 1936, Serial No. 58,253

10 Claims. (Cl. 128—146)

This invention relates to improvements in respirators. It has for an object the production of an improved device to be used for protecting the user from dust, smoke, and noxious 5 gases of various kinds.

One of the objects of the invention is to provide a simple, practical, and efficient respirator of the character described.

Another object is to provide a light weight 10 respirator adapted to permit good vision.

Another object is to provide a respirator of the character described having a large area for filtering and also adapted for easy breathing.

A further object is to provide a device of the 15 character described which is comfortable and possesses high efficiency for catching dust, dirt, smoke, and the like.

A still further object is to provide a respirator having a readily removable filtering pad 20 requiring no adjusting or locking parts.

An additional object is to provide a respirator wherein substantially the entire area of the filter pad is available for filtering purposes.

Other objects and advantages will become apparent and be brought out more fully in the following specification, reference being had to the accompanying drawings, wherein:

Fig. 1 is a plan section of a preferred embodiment of my invention, taken on the line 1—1 of Fig. 2;

Fig. 2 is a central sectional elevation taken along the line 2—2 of Fig. 1;

Fig. 3 is a perspective view of the invention illustrating the mode of attachment of the filter pad to the device; and

Fig. 4 is an exploded view in section of one of the filtering elements.

Referring more particularly to the drawings and especially to Fig. 2, I show a respirator having a body portion 10 provided with cut-outs 11 at the top and bottom to accommodate the nose of a wearer, the body portion 10 being reversible. I also show a bulbous valve housing 12 having a pair of exhaust openings 13, the housing 12 inclosing a valve seat 14 which cooperates with an exhaust valve 15, the body 10 having also a rearwardly extending right wall 16 and a left wall 17, each provided with a circular aperture 18. A head strap 19 is provided 45 and is secured to walls 16 and 17 respectively by a nut 20 and bolt 21. The foregoing features are similar in all respects to the type of respirator covered by United States patent application copending herewith, Serial No. 56,255, filed December 26, 1935.

The subject matter of my present application resides essentially in an improved type of filter holder secured to the side walls 16 and 17. The filter holders, of which there is a pair, each consists of a metallic retaining plate 22, preferably circular in outline although it will be understood that the precise shape is not essential to my invention as the same may be either square, oval, or otherwise, as desired. Associated with the retaining plate 22 is a filtering 5 pad element 23 of similar outline to the plate 22 and of the same or slightly larger area. Plate 22 has a circumferential curved edge portion 24 providing a cavity 24a and has an inwardly deflected flanged edge portion 25. Plate 22 is further provided with a central extrusion or hump 26 and a plurality of similar extruded portions 27 located around the central extrusion 26.

Fig. 4 clearly discloses a flanged tubular locking member 28, the tubular portion of which is 20 adapted to be passed through aperture 18, and a flanged collar 29 is provided, having a number of lateral openings 30 and a sloping upward edge portion 31, the locking member 28 and the collar 29 being adapted to form a flanged joint 25 32 (Fig. 1) by which the plate 22 is secured to the side walls 16 and 17 of the body portion 10 of the respirator. It will be observed that nut 20 of the head strap 19 will lie in the cavity formed by the central extrusion 26, thus 30 permitting the filter plate 22 to lie substantially flat against the face of the wearer. The filter pad 23 is secured in place by the flanged edge 25 of plate 22, the pad being normally somewhat thicker than the space provided between the 35 edge 25 and the base portion of the plate 22, such that the pad 23 must be compressed somewhat at the edges in order to make a secure fit, this fit being further assisted by the sloping upper edge of the collar 29, and when the pad 40 23 is placed in position the edge portion nearest the collar 22 is first slipped under the flange 25 as shown in Fig. 3, whereupon the rest of the edge of the pad may be slipped under the circular flange 25. The pad will thus be seen 45 to cover the bottom of plate 22 completely, although separated from the plate by the extrusions 26 and 27 and the top edge of the collar 29, and since the pad 23 is formed to be slightly larger in area when flat than that of the plate 50 22, it will be obvious that a tight and secure circumferential fit is made with the pad and the edge 24 of the plate 22. It will be further obvious that substantially the entire inner surface of the pad 23 is available for the trans-

mission of air since this surface is separated from the surface of the plate 22 by the extrusions 26 and 27 and the collar 29, resulting in a number of passageways between the interior surface of the pad 23 and the openings 30 through which the air may pass into a tubular passage provided by member 28 to the interior of the body 10 of the respirator. The flanged portion 25 insures a tight fit with the edge portion of the pad 23, preventing any leakage of air and dust around the edge of the pad 23.

It will thus be apparent that the invention as described achieves all of the objects hereinbefore stated for the device.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. In a respirator, a body portion having an exhaust valve and an intake port, said intake port having filter means comprising a corrugated plate, an aperture in said plate registering with said intake port, and a filter pad secured to said plate over said aperture.

2. In a respirator, a body portion having an exhaust valve and an intake port, said intake port having filter means comprising a plate, an aperture in said plate registering with said intake port, and a filter pad secured to said plate over said aperture, said plate having a plurality of raised portions adapted to provide a space between said pad and plate.

3. In a respirator, a body portion having an exhaust valve and an intake port, said intake port having filter means comprising a plate, an aperture in said plate registering with said intake port, the periphery of said plate being formed with an inwardly opening groove and a filter pad over said aperture and secured to said plate with the edge portions tucked into said groove.

4. In a respirator, a body portion having an exhaust valve and an intake port, said intake port having filter means comprising a plate, an aperture in said plate registering with said intake port, the periphery of said plate being formed with an inwardly opening groove and a filter pad over said aperture and having its edges tucked into said groove to removably

secure the same to said plate at the edge portions thereof.

5. In a respirator, a body portion having an exhaust valve and an intake port, said intake port having filter means comprising a plate, an aperture in said plate registering with said intake port, and a filter pad over said aperture, said plate having its periphery curved inwardly to form means to secure said filter pad thereto.

6. In a respirator, a body portion having an exhaust valve and an intake port, said intake port having filter means comprising a plate, an aperture in said plate registering with said intake port, and a filter pad over said aperture, said plate having its periphery curved inwardly to form a peripheral pocket to receive the edge of said filter pad, and the edge of said inturned portion being adapted to clamp the filter pad, substantially as described.

7. In a respirator, a body portion having an exhaust valve and an intake port, said intake port having filter means comprising a plate, an aperture in said plate registering with said intake port, a filter pad over said aperture, and means to secure said filter pad in substantial spaced relation to said plate, said means comprising a plurality of extrusions on said plate.

8. In a respirator, a body portion having an exhaust valve and an intake port, said intake port having filter means comprising a plate, an aperture in said plate registering with said intake port, a filter pad over said aperture, and means to secure said filter pad in substantial spaced relation to said plate, said means comprising a plurality of extrusions on said plate and a tubular member extending through said aperture.

9. In a respirator, a body portion having an exhaust valve and an intake port, said intake port having filter means comprising a plate, an aperture in said plate registering with said intake port, a filter pad over said aperture, and means to secure said filter pad in substantial spaced relation to said plate, said means comprising a plurality of extrusions on said plate and a tubular member extending through said aperture, said tubular member having a lateral aperture adapted for passage of air from the inner side of said filter pad into said body portion.

10. In a respirator, a body portion having an intake port, said intake port having filter means comprising a corrugated plate, an aperture in said plate registering with said intake port, and a filter pad secured to said plate over said aperture.

HARVEY S. COVER.
